REFRIGERATOR

Norman J. Yerkes, Greenville, Mich., assignor, by
mesne assignments, to Gibson Refrigerator
Company, Greenville, Mich., a corporation of
Michigan

Application April 23, 1941, Serial No. 389,828

4 Claims. (Cl. 62—116)

This invention relates to refrigerating apparatus of the compressor-condenser-expander type; and more particularly to a novel arrangement of the compressor and condenser with a refrigerator cabinet whereby cooling air is caused to circulate through the condenser and over the compressor solely by thermal action.

In devices of the prior art where the compressor and condenser have been air cooled, it has been the practice to utilize a fan for circulating air over the compressor and through the condenser. Various attempts have been made to dispense with the fan and effect a circulation of cooling air solely by thermal action. However, the prior devices of this latter class have not been entirely satisfactory because of the fact that in certain designs the cooling air passes over the compressor before it passes through the condenser, with a resulting loss of efficiency in the condenser. Attempts have been made to overcome this objection by locating the condenser below the compressor and in a generally horizontal position. Such an arrangement cannot be utilized effectively in many modern refrigerators, because the side walls of the cabinets extend to the floor. That prevents the circulation of air beneath the bottom of the cabinet and up through the condenser.

It is the principal object of the present invention to provide an arrangement of parts whereby the compressor and condenser are cooled by air which is circulated solely by thermal action, and wherein the above recited disadvantages of the prior art are avoided. This object is accomplished by mounting the compressor within the machinery compartment at the bottom of the cabinet adjacent an open side thereof, providing a vertically extending air conducting flue having its lower end located adjacent the upper extremity of the open side of the machinery compartment, and mounting an upright condenser in an inclined position with its lower extremity juxtaposed to the lower edge of the open side of the machinery compartment and its upper extremity located outside of the machinery compartment and below but within the lateral confines of the flue. With this arrangement the heat generated within the compressor and condenser induces a circulation of air along a plurality of pathways. A portion of the cooling air passes through the condenser into the machinery compartment, over the compressor and thence into the flue without passing through the condenser a second time. Other portions of the cooling air pass through the condenser and into the flue exteriorly of the ma-

chinery compartment. By this arrangement of parts an entirely satisfactory cooling of the compressor and condenser is obtained without sacrificing the advantage of having the condenser arranged in an upright position whereby the compressed refrigerant can be admitted at the top of the condenser as it is received from the compressor and withdrawn as a liquid from the bottom of the condenser.

This object and others ancillary thereto will become more apparent in the following specification when read in connection with the accompanying drawing, wherein—

Figure 1 is a top plan view of a refrigerator embodying the invention;

Figure 2 is a rear elevational view of the refrigerator, a part thereof being broken away to more clearly disclose the construction thereof; and

Figure 3 is a side elevational view of the refrigerator, a part of the side wall being broken away to show the arrangement of the condenser and compressor.

The invention is embodied in refrigerating apparatus comprising a cabinet 10. In the upper part of the cabinet is a storage compartment, access to which is effected by a door 11. Below the storage compartment is a machinery compartment 12. The machinery compartment is enclosed on three upright sides by a door 13 and the two side walls of the refrigerator cabinet. The bottom of the machinery compartment is formed by the base 9 of the refrigerator cabinet. In the back of the machinery compartment 12 is a large rectangular opening 14. The vertical edges of the opening are formed by portions of the back wall 15 of the refrigerator cabinet. Specifically, these portions are two vertically arranged metal plates 16 attached to the opposite side walls of the cabinet. On the adjacent edges of the plate 16 are oppositely extending integral tabs 17 and 18. The two tabs 17 and 18 on each plate 16 are arranged in the same vertical plane.

Located between the plates 16 and attached to the tabs 17 and 18 is a condenser 19. The condenser comprises a conduit 20 bent into serpentine shape, as shown in Figure 2, and a plurality of heat radiating fins 21. The various loops of the conduit 20 are arranged in a single plane and the condenser is inclined slightly from the perpendicular, as shown in Figure 3. The lower edge of the condenser is mounted just within the machinery compartment and adjacent the lower edge of the opening 14. The upper edge of the condenser 19 is located outside of the machinery

compartment and is spaced from the upper edge of the opening 14 to permit the escape of warm air from the machinery compartment without necessitating its passage through the condenser.

A compressor 22 of the air-cooled type is mounted within the machinery compartment 12 centrally of, and as near to the condenser 19 as it can be conveniently located. The compressor is connected by a pipe 8 to the conduit 20 at the upper edge of the condenser. The other end of the conduit 20 at the lower edge of the condenser is connected in the usual way to a conventional evaporator (not shown). The connections are such that the warm, gaseous refrigerant is pumped by the compressor into the condenser 19 at the upper edge of the latter, and as the refrigerant liquifies it gravitates downwardly. The liquid refrigerant collects in the lower part of the condenser, effectively preventing the escape of unliquefied refrigerant into the evaporator.

A flue 23 is attached to the back wall 15 of the refrigerator cabinet. The flue may be made of any suitable material. It is a three-sided structure, open at its top and bottom ends. Together with the back wall 15 it forms a chimney for carrying away the heated air from the condenser 19 and the machinery compartment 12. The lower end of the flue 23 is located in proximity to the upper edge of the condenser and to the upper edge of the opening 14 in the machinery compartment.

The effect of the arrangement of the condenser 19, compressor 22 and flue 23, insofar as the circulation of air is concerned, is practically self-evident from Figure 3 of the drawing, wherein the arrows indicate in a general way the paths of the air. When the cooling system of the refrigerator is in operation, the warm refrigerant is pumped by the compressor 22 into the condenser 19 where it gives up its heat to the air surrounding the condenser. As the air absorbs heat from the condenser 19, the air rises and flows upwardly and inwardly through the condenser. Some of the air near the top of the condenser flows directly into the flue 23, while the air passing through the lower part of the condenser flows inwardly and over the compressor 22 before it rises into the upper part of the machinery compartment and out through the upper part of the opening 14. The compressor is warmer than the condenser and the air that passes through the condenser. Hence the cooling air that passes over the exterior of the compressor absorbs considerable heat therefrom. Thus, the air cools the compressor and as the temperature of the air rises in consequence of the absorption of heat, it tends to flow more swiftly out of the machinery compartment and up the flue 23. The chimney effect of the flue is thereby increased and the overall efficiency of the condenser-compressor is improved because of rapid flow of cooling air. All of the air passing inwardly through the condenser 19 escapes into the flue 23 between the adjacent edges of the condenser and the upper edge of the opening 14. This heated air does not repass through the condenser.

With the arrangement of parts disclosed, the opening 14 is the only opening in the machinery compartment necessary for the adequate circulation of cooling air. In fact, for most effective circulation of cooling air, additional openings to the machinery compartment are undesirable.

From the foregoing it will be seen that the invention provides a novel arrangement of the compressor and condenser for refrigerating apparatus which effectively avoids the disadvantages inherent in the prior art devices.

The scope of the invention is indicated in the appended claims.

I claim:

1. Refrigerating apparatus comprising a cabinet having a machinery compartment, said compartment having an opening in one upright side thereof, said opening being the principal outlet opening for air from the machinery compartment, a condenser mounted in an inclined position in close proximity to said opening, said condenser being substantially coextensive with said opening, the lower edge of said condenser being adjacent the bottom of the compartment and the upper edge being outside of the compartment and spaced from the adjacent edge of the opening, and a compressor within the compartment adjacent the condenser.
2. Refrigerating apparatus comprising a cabinet having a machinery compartment, said compartment having an opening in one upright side thereof, a condenser mounted in an inclined position in close proximity to said opening, the lower edge of said condenser being closely adjacent the bottom of the compartment and the upper edge being outside of the compartment and spaced from the adjacent edge of the opening, and a vertically extending flue secured to a wall of the refrigerator cabinet and having its lower end in proximity to the upper edge of the condenser whereby to induce the circulation of air inwardly through the condenser and upwardly into the flue between the upper edges of the condenser and the opening in the machinery compartment.
3. Refrigerating apparatus comprising a cabinet having a machinery compartment, said compartment having an opening in one upright side thereof, a condenser mounted in an inclined position in said opening, the lower edge of said condenser being within the compartment and the upper edge being outside of the compartment and spaced from the adjacent edge of the opening, a compressor within the compartment adjacent the condenser, and a vertically extending flue secured to a wall of the refrigerator cabinet and having its lower end in proximity to the upper edge of the condenser whereby to induce the circulation of air inwardly through the condenser, over the compressor, and into the flue between the upper edges of the condenser and the opening in the machinery compartment.
4. Refrigerating apparatus comprising a cabinet having a machinery compartment, said compartment having an opening in one upright side thereof, a condenser mounted in an upwardly and outwardly inclined position adjacent said opening, the lower edge of the condenser being juxtaposed to the lower edge of the opening and the upper edge of the condenser being spaced outwardly from the upper edge of the opening whereby to provide a passageway for the escape of air from the compartment between the upper edge of said opening and the condenser, and means located exteriorly of the cabinet and adjacent said passageway for inducing a current of air outwardly through said passageway.

NORMAN J. YERKES.
